CLAIM

The ornamental design for a hall effect sensor holder, as shown and described.

DESCRIPTION

FIG. 1 is a perspective view of a hall effect sensor holder;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof at an installed position on an electric motor.

Portions of the views shown in phantom form no part of the design.
